UNITED STATES PATENT OFFICE.

EDWARD D. LEWIS, OF CHICAGO, ILLINOIS.

CURTAIN-SUPPORTER.

No. 826,176.

Specification of Letters Patent.

Patented July 17, 1906.

Application filed March 27, 1906. Serial No. 308,331.

To all whom it may concern:

Be it known that I, EDWARD D. LEWIS, a citizen of the United States, residing at Chicago, in the county of Cook and State of Illinois, have invented certain new and useful Improvements in Curtain-Supporters, of which the following is a specification.

This invention relates to curtains and other hangings, and has for its object to provide a neat, simple, and convenient support for draperies and the like and by means of which they may be easily and quickly taken down and replaced.

In the accompanying drawings, forming a part of this specification, Figure 1 is a view of a device embodying my invention in perspective. Fig. 2 is a central section of the same.

In the drawings, A designates a window-casing, and B a pair of curtains. Near each side and top of the window is mounted a socket C, comprising a tube or cup provided at one side with a screw D and shoulder E. This may of course be screwed in place without the use of any tool whatever and is therefore very convenient to put in place. Into the top of this tubular socket fits a plug F, having an eye G at the top. The part that takes the hem of the curtain is a pretty stiff coil-spring H, and this preferably connects with an eye G at each end by a snap-hook I,

which admits of easy detachment from the plugs when the curtain is to be stripped off the coil and makes it possible to close the terminal eyes of the coil, so that there is no projecting end of wire to catch in taking off the curtain. 35

In putting up the curtain the device is very convenient, as the operator has a good-sized piece in his hand with which to stretch the coil and to slip into the socket. 40

Having thus described my invention, what I claim as new, and desire to secure by Letters Patent, is—

1. A curtain - supporter, comprising a 45 socket with a screw fixed in one side, a plug to fit said socket, having an eye to engage a hook, and a coil-spring to connect with said eye.

2. A curtain - supporter, comprising a 50 socket with a screw fixed at one side, a plug to fit said socket, having an upwardly - projecting eye, a coil-spring to string the curtain on, and snap-hook to removably connect the plug and coil-spring. 55

In testimony whereof I affix my signature in presence of two witnesses.

EDWARD D. LEWIS.
